UNITED STATES PATENT OFFICE.

ALBERT H. MORTON, OF LOWELL, MASSACHUSETTS.

COTTON-DISTRIBUTING APPARATUS.

No. 881,940.

Specification of Letters Patent. Patented March 17, 1908.

Application filed November 9, 1904. Serial No. 232,041.

To all whom it may concern:

Be it known that I, ALBERT H. MORTON, a citizen of the United States, residing at Lowell, in the county of Middlesex and State of Massachusetts, have invented certain new and useful Improvements in Cotton - Distributing Apparatus; and I do hereby declare the following to be a full, clear, and exact description of the invention, such as will enable others skilled in the art to which it appertains to make and use the same.

The present invention relates to improvements in cotton distributing apparatus for cotton mills.

In a cotton mill, as usually arranged, the storehouse in which the bales of cotton are stored and opened, is, for convenience, and for protection against fire, isolated from the building in which the picker-room is located, and the cotton is transferred from the opening room to the picker room through a pneumatic conveyer terminating in a condenser which delivers the cotton in the picker room. The cotton which accumulates at the condenser is then carried by operatives to the feeders which automatically furnish to the openers and breaker-lappers with which they are connected a uniform and constant supply of cotton as long as they are kept supplied by the operatives. In this method of handling and distributing the cotton the uniform operation of the feeders and the machines supplied thereby depends upon the vigilance of the operatives who supply them with cotton, and as one operative can supply only a few feeders, the expense of this method of distribution is considerable. This method is further objectionable in that the cotton which collects in bulk at the condenser is a source of fire risk, so that it is necessary to construct a bin to protect the cotton.

The object of the present invention is to re-organize and improve the methods and apparatus for conveying and distributing the cotton in cotton mills; and the invention consists in the apparatus hereinafter described and particularly defined in the claims.

One feature of the invention consists in providing an endless belt conveyer constantly running in the same direction for carrying cotton to a plurality of receptacles with a plurality of independent devices for diverting the cotton from the belt to the receptacles, such diverting means being independently controlled by the amount of cotton in

each receptacle and located at intervals along the belt.

Another feature consists in combination with a pneumatic conveyer such as that by which the cotton is brought from the opener room to the picker room, of a condenser for collecting cotton brought by the conveyer and an endless belt arranged to receive the cotton from the condenser and to distribute it to a plurality of receptacles such as the feeders of openers and breaker-lappers and means for controlling the delivery of cotton from the endless belt into each receptacle according to the amount of cotton therein.

Other features of the invention are defined in the claims.

In the drawings illustrating the preferred form of the invention, Figure 1 is a plan view showing a condenser, a mechanical conveyer, and a row of feeders supplied thereby, and Fig. 2 is a front elevation of the same parts. Fig. 3 is an end elevation showing the condenser, conveyer, and one feeder, and the blower and the exhauster by which the air is forced through the pneumatic conveyer tube and exhausted from the condenser. Fig. 4 is a side view of a feeder and a sectional view of the mechanical conveyer, and Fig. 5 is an enlarged view of a part of the apparatus shown in Fig. 4, showing particularly the automatic apparatus for controlling the delivery of cotton into the feeder.

The pneumatic conveyer for transferring the cotton from the opening room to the picker room may be of any usual or suitable form, and it is indicated in Fig. 3 by the tube 1 connected with the blower 2 by which the current of air and cotton is forced through the tube. The condenser 3 into which the cotton is delivered and by which it is separated from the air current may also be of the usual form. The air is exhausted from the condenser through a pipe 4 by an exhauster 5.

A mechanical conveyer for receiving the cotton from the condenser and distributing it to the feeders is indicated in a general way by the reference character 6. In the illustrated embodiment of the invention it is in the form of an endless belt 7 passing over rollers 8 and actuated constantly by suitable power connections. The cotton is delivered by the condenser to the upper surface of the belt and this portion of the belt moves constantly in the direction of the arrow (Fig. 1) so as to carry the cotton away from the con-

denser. The sides of the belt are inclosed by walls to retain the cotton thereon. The feeders 10 are arranged in a row over which the conveyer 6 passes and above each feeder 5 there is an opening 10 $\times$ in the wall 9 through which the cotton may be discharged from the conveyer into the hopper of the feeder. The means by which the cotton is discharged from the conveyer comprise swinging gates 10 11 arranged to form normally a portion of the side walls of the conveyer, capable of being swung into an oblique position across the belt as at 12 in Fig. 1 when it is desired to discharge the cotton into the feeder. The 15 cotton is deflected by the gates out of the openings 10 $\times$.

In the illustrated embodiment of the invention the means for operating the gates 11 are automatic, being actuated by suitable 20 power connections and controlled by the cotton in the feeder. The automatic means for controlling the gates are shown particularly in Figs. 4 and 5, and are constructed as follows:—In each feeder there is a feeler 13 25 comprising parallel bars connected to the levers 14 pivoted at 15 upon supports secured to the frame of the feeder. One of the levers 14 has an arm carrying a toothed segment 16 engaging a segmental gear 17 to 30 which a weight 18 is secured by a lever arm. This weight tends constantly to swing the feeler inward but so long as a sufficient supply of cotton remains in the feeder this tendency is resisted by the cotton and the 35 feeler is kept in the position shown in Fig. 4. It is to be noted, however, that this tendency is the greater when the amount of cotton in the receptacle is the less and the less when the amount of cotton in the receptacle is the 40 more. This is a feature hereinafter alluded to in connection with the operation of the apparatus. To the upper arm 19 of the lever 14 is pivoted a shifter rod 20 which 45 slides through a hole in the end of an arm 21 of a trip lever 22. The trip lever is pivoted at 23 upon a lever 24 pivoted at 25 to the side of the feeder. The upper end of the arm 24 is connected by a link 26 with the gate 11, which is pivoted at 27 to the side 50 wall of the conveyer. A link 28 is connected with a crank pin 29 on a constantly rotating part of the feeder mechanism, and at its other end is pivotally connected with a slide 30 moving in a sleeve 31 fixed to the lever 24. 55 The slide carried dogs 32 and 33. The slide is constantly reciprocated by means of the link 28 and pin 29 and when the trip lever 22 is moved so that one or the other of its arms 34 and 35 is in position to be engaged 60 by the corresponding dog 32 or 33, the lever 24 will by these means be moved so as to close or open the gate as the case may be. The rod 20 carries collars 36 and 37 which 65 engage the arm 21 of the trip lever and move it to one side or the other to cause the arms

34 and 35 to engage their respective dogs. The trip lever 22 carries a spring actuated pawl 38 engaging a tooth 39 on the lever 24 and serving to keep it always to one side or the other so that one or the other of the arms 70 34 and 35 is in position to engage a dog. The lever 24 carries a roll 40 engaging a lever 41 pivoted at 42 on the frame of the conveyer and having a notch 43 and a shoulder 44 by which the roll 40 and the lever 24 are retained in position after the gate has been fully opened or fully closed, the lever 41 being pressed upward by the spring plunger 45. 75

Assuming the parts to be in the position shown in Fig. 5, in which the feeler 13 is pressed back by a supply of cotton in the feeder and the gate 11 is open so as to permit the cotton to pass by without discharging into the feeder, suppose the supply of cotton to diminish until the feeler moves to the left under the influence of the weight 18. The rod 20 will be drawn to the right and the collar 37 engaging the arm 21 of the trip lever will swing the trip lever so as to raise the arm 34 out of operative position and lower the arm 35 into position to be engaged by the dog 33. Upon the next succeeding right-hand movement of the slide 30 the dog 33 will force the trip lever and the lever 24 to the right, thereby causing the gate 11 to be swung into oblique position across the belt to divert cotton therefrom through the opening in the wall opposite the gate into the feeder. It is to be observed that the stream severing end of the gate (i. e., the portion of the gate that cuts the stream and initiates the flow from the gate at that place) always projects in the direction of motion of the belt and never obstructs or interrupts the flow of the approaching cotton. The parts will remain in this position until the feeder is again filled, the dog 33 merely reciprocating idly after having moved the trip lever to the right as far as it will go. When a sufficient amount of cotton has accumulated to again force the feeler back and raise the weight 18 the reverse operation will take place and the gate will open and cease to discharge cotton into the feeder. 100 105

It is to be noted that when the weight 18 is in raised position its tendency to fall and to move the feeler is slight, owing to its position nearly above its pivotal support, while its effectiveness is much greater when it is in its lowered position, with the arm upon which it is supported in horizontal position. From this it results that after the weight has fallen and the gate has been opened a considerable quantity of cotton must accumulate in the feeder before the weight will be overcome and the gate closed, while after enough cotton has accumulated to raise the weight a considerable diminution must occur before the weight can again fall. This feature is of importance to the best embodiment of the invention since it prevents the automatic 110 115 120 125 130

mechanism from operating frequently upon inconsiderable fluctuations of the amount of cotton in the feeder, and secures the diverting of cotton to the feeder when the amount of cotton therein falls below a certain minimum, and the cessation of the discharge of cotton upon the attainment of a certain maximum amount therein. Furthermore, it is to be noted that with this construction when the amount of cotton in the hopper falls to such an extent that it approaches the minimum, the weight 18 will have moved from the position shown in Fig. 5 toward the horizontal thereby increasing its effectiveness to move the shifter. Also that when the amount of cotton approaches the maximum, the weight 18 is raised towards the vertical, and therefore opposes less and less the movement of the feeler under the influence 20 of the cotton. Thus the effectiveness of the weight to move the shifter increases when the cotton recedes and decreases when the cotton increases in amount.

Although in the illustrated embodiment of the invention the means for periodically diverting the cotton on the conveyer belt into the hopper of the feeder are automatic and such an arrangement is preferable because it dispenses with the necessity of constant attention on the part of the operative, the use of such automatic means is not essential to the invention, in its broader aspects, for although the automatic apparatus be dispensed with and the gates be operated by hand, the apparatus, comprising the pneumatic tube, blowers, condenser, belt conveyer, and feeders, will still constitute apparatus operating continuously to convey cotton from the opening room direct to the breaker-lappers or other machines without intermediate handling, and with only such supervision as is necessary to open and shut the gates at the proper times to supply the feeders as they become empty. Moreover, the invention is not limited to the details of construction set forth in the description of the preferred embodiment, but may be embodied in other forms broadly defined by the claims.

What is claimed is:—

1. An apparatus for conveying and distributing cotton to a plurality of receptacles arranged in a row, consisting of an endless belt constantly running in the same direction over the several receptacles, adapted to receive cotton at one end and to carry it over the receptacles, combined with means at each receptacle automatically controlled by the quantity of cotton therein, for diverting the cotton directly from the belt into such receptacles substantially as described.

2. Cotton distributing apparatus for cotton mills, having, in combination, a plurality of receptacles, a pneumatic conveyer, a condenser connected with said conveyer, a mechanical conveyer constructed and arranged

to receive cotton from the condenser and to convey it to the receptacles and means for removing the cotton from the mechanical conveyer and diverting it into each receptacle substantially as described.

3. Cotton distributing apparatus for cotton mills, having, in combination, a plurality of receptacles for cotton, a pneumatic conveyer, a condenser connected with said conveyer, an endless belt conveyer for transferring the cotton from the condenser to the receptacles, and a movable gate at each receptacle for diverting the cotton from the belt into the receptacle, substantially as described.

4. An apparatus for conveying and distributing cotton to a plurality of receptacles arranged in a row, consisting of an endless belt constantly running in the same direction over the several receptacles, adapted to receive cotton at one end and to carry it over the receptacles, combined with a gate at each receptacle for diverting the cotton directly from the belt into such receptacle and automatic means at each receptacle for controlling the operation of the gate according to the amount of cotton in the receptacle substantially as described.

5. Cotton distributing apparatus for cotton mills, having, in combination, a receptacle for cotton, a conveyer for supplying cotton thereto, a gate for controlling the delivery of cotton from the conveyer into the receptacle, a feeler for detecting the amount of cotton in the receptacle, and mechanism controlled by the feeler for operating the gate, substantially as described.

6. Cotton distributing apparatus for cotton mills, having, in combination, a receptacle for cotton, a conveyer for supplying cotton thereto, a gate for controlling the delivery of cotton from the conveyer into the receptacle, mechanism for operating the gate comprising a constantly operating power member normally disconnected from the gate, a feeler within the receptacle, and connections between the feeler and the gate-operating mechanism for throwing the power member and the gate into operative connection, substantially as described.

7. An apparatus for conveying and distributing cotton to a plurality of receptacles arranged in a row, consisting of a pneumatic conveyer, an endless belt constantly running in the same direction, the pneumatic conveyer discharging cotton upon the end of the endless belt to be carried thereby over the receptacles, combined with means at each receptacle automatically controlled by the quantity of cotton therein for diverting the cotton directly from the belt into such receptacle, substantially as described.

8. Cotton distributing apparatus for cotton mills, having, in combination, a pneumatic conveyer pipe, a blower, a condenser,

an exhauster therefor, a plurality of cotton feeders, an endless belt conveyer constantly running adjacent to the feeders in the same direction upon which conveyer the condenser 5 discharges cotton, and switches or deflectors at each feeder to divert the cotton from the belt conveyer into the feeders, substantially as described.

9. Cotton distributing apparatus for cotton mills, having, in combination, a pneumatic conveyer pipe, a fan, a condenser, a plurality of cotton feeders, an endless belt conveyer constantly running adjacent to the feeders in the same direction upon which conveyer the condenser 10 discharges cotton, and switches or deflectors at each feeder to divert the cotton from the belt conveyer into the feeders, substantially as described.

10. Cotton distributing apparatus for cotton mills, having, in combination, a plurality of receptacles for cotton, a conveyer for supplying cotton thereto, and automatic means, comprising a power member, for controlling the discharge of cotton from the conveyer 15 into each receptacle governed by the amount therein, substantially as described.

11. Cotton distributing apparatus for cotton mills, having, in combination, a plurality of receptacles for cotton, a conveyer for conveying cotton thereto, means at each receptacle for removing the cotton from the conveyer and diverting it into the receptacle, and automatic means actuated by power and controlled by the amount of cotton in the 20 receptacles for throwing the removing means respectively into and out of operation, substantially as described.

12. An apparatus for conveying and distributing cotton to a plurality of receptacles arranged in a row, consisting of a pneumatic conveyer, an endless belt constantly running in the same direction, the pneumatic conveyer discharging cotton upon the end of the endless belt to be carried thereby over the 25 receptacles, combined with a gate at each receptacle for diverting the cotton directly from the belt into such receptacle and automatic means at each receptacle for controlling the operation of the gate according 30 to the amount of cotton in the receptacle, substantially as described.

13. An apparatus for conveying and distributing cotton to a plurality of receptacles arranged in a row, consisting of a pneumatic conveyer, an endless belt constantly running in the same direction, the pneumatic conveyer discharging cotton upon the endless belt to be carried thereby over the receptacles, combined with means at each receptacle for diverting the cotton directly from the belt into such receptacle without interrupting the flow of the approaching cotton, substantially as described.

14. Cotton distributing apparatus for cotton mills, having, in combination, a plurality

of receptacles for cotton, a pneumatic conveyer, a condenser connected with said conveyer, a mechanical conveyer connecting the condenser and the receptacles for continuously conveying a supply of cotton and automatic means, including a power member, for controlling the discharge of the cotton from the mechanical conveyer into each receptacle, according to the amount therein, substantially as described.

15. An apparatus for conveying and distributing cotton to a plurality of receptacles arranged in a row, consisting of a pneumatic conveyer, an endless belt constantly running in the same direction, the pneumatic conveyer discharging cotton upon the end of the endless belt to be carried thereby over the receptacles, combined with a gate at each receptacle for diverting the cotton directly from the belt into such receptacle and means at each receptacle for controlling the operation of the gate according to the amount of cotton in the receptacle, substantially as described.

16. Cotton distributing apparatus for cotton mills, having, in combination, a receptacle, a conveyer for delivering cotton thereto, and means for controlling the delivery of cotton from the conveyer into the receptacle comprising a feeler located in the receptacle and a device tending to move the feeler in the direction to cause the controlling means to deliver cotton to the receptacle, substantially as described.

17. Cotton distributing apparatus for cotton mills, having, in combination, a receptacle, a conveyer for delivering cotton thereto, and means for controlling the delivery of cotton from the conveyer into the receptacle comprising a feeler located in the receptacle and a device tending to move the feeler in the direction to cause the controlling means to deliver cotton to the receptacle acting with increased effectiveness with a decrease in the amount of cotton in the receptacle, substantially as described.

18. An apparatus for conveying and distributing cotton to a plurality of receptacles, consisting of an endless belt constantly running in the same direction and a plurality of independent devices for diverting the cotton from said belt into each of said receptacles, said devices being independently controlled by the amount of cotton in each receptacle and located at intervals along the belt, substantially as described.

19. Apparatus for distributing cotton, having, in combination, a belt constantly running in the same direction, side walls for the belt having openings therein, and deflectors located opposite the openings through which they divert the cotton constructed to be moved into oblique position across the belt to divert the cotton therefrom, always maintaining their stream severing

125
130

ends projecting in the direction of motion of the belt so that they do not interrupt the flow of approaching cotton.

20. Apparatus for distributing cotton, 5 having, in combination, a belt constantly running in the same direction, side walls for the belt having openings therein, and deflectors hinged opposite the openings through which they divert the cotton constructed 10 to be swung into position obliquely across the belt to divert the cotton therefrom, always maintaining their stream severing ends projecting in the direction of motion of the belt so that they do not interrupt the 15 flow of approaching cotton.

21. Apparatus for distributing cotton, having, in combination, a belt constantly running in the same direction, side walls for the belt having openings therein, deflectors 20 located opposite the openings, and means for moving the deflectors into position obliquely across the belt to divert the cotton therefrom.

22. Apparatus for distributing cotton, 25 having, in combination, a belt constantly running in the same direction, side walls for the belt having openings therein, deflectors hinged opposite the openings, and means for swinging the deflectors into oblique position 30 across the belt to divert the cotton therefrom.

23. Apparatus for distributing cotton, having, in combination, a belt constantly running in the same direction over a plurality 35 of receptacles, side walls for the belt having openings therein, deflectors located opposite the openings, and means automatically controlled by the quantity of cotton in the receptacle for moving the deflectors into 40 oblique position across the belt to divert the cotton therefrom.

24. Apparatus for distributing cotton, having, in combination, a belt constantly running in the same direction over a plurality 45 of receptacles, side walls for the belt having openings therein, deflectors hinged opposite the openings, and means automatically controlled by the quantity of cotton in the receptacles for swinging the deflectors into oblique position across the belt to divert the cotton therefrom.

25. Apparatus for distributing cotton, having, in combination, a belt constantly running in the same direction, side walls for 55 the belt having openings therein, deflectors located opposite the openings constructed to be moved into oblique position across the belt to divert the cotton therefrom, and means for holding the deflectors in diverting 60 position.

26. Apparatus for distributing cotton, having, in combination, a belt constantly running in the same direction, side walls for the belt having openings therein, deflectors 65 hinged opposite the openings constructed to

be swung into oblique position across the belt to divert the cotton therefrom, and means for holding the deflectors in diverting position.

27. Apparatus for distributing cotton, 70 having, in combination, a belt constantly running in the same direction, side walls for the belt having openings therein, and deflectors hinged opposite the openings at their ends nearest to or toward the end of the belt 75 where the cotton is supplied thereto.

28. Apparatus for distributing cotton, having in combination, a belt constantly running in the same direction, side walls for the belt having openings therein, and deflectors constructed to be moved into oblique 80 position across the belt always maintaining their stream severing ends projecting in the direction of motion of the belt so that they do not interrupt the flow of approaching 85 cotton.

29. Apparatus for distributing cotton, having, in combination, a traveling belt, a gate, a gate-operating lever, a trip-lever pivotally mounted on the gate-operating lever, a 90 reciprocating part, a sleeve on the gate-operating lever for supporting the reciprocating part, means on said part for engagement with the trip-lever, having provision for accelerating the tripping movement. 95

30. Apparatus for distributing cotton, having, in combination, a traveling belt, a gate, a gate-operating lever, a trip-lever pivotally mounted on the gate-operating lever, a reciprocating part, and means on said part 100 for engagement with the trip-lever, having provision for accelerating the tripping movement.

31. Apparatus for distributing cotton, having, in combination, a traveling belt, a 105 gate, a gate-operating lever, connections between the lever and the gate and means for locking the gate.

32. Apparatus for distributing cotton, having, in combination, a traveling belt, a 110 gate, a gate-operating lever, a link connecting the lever and the gate, a hinge for the gate, and a part having a notch coöperating with the lever to hold the gate.

33. Apparatus for distributing cotton, having, in combination, a traveling belt, a gate, a gate-operating lever, connections between the lever and the gate, and a part having a notch coöperating with the lever and a stop coöperating with the gate which taken 120 together are adapted to hold the gate in position.

34. Apparatus for distributing cotton, having, in combination, a traveling belt, a gate, a gate-operating lever, connections between the lever and the gate, and a part having a notch in spring-controlled coöperation with the lever to hold the gate in position. 125

35. Apparatus for distributing cotton, having, in combination, a traveling belt, a 130

gate, a gate - operating lever, a constantly rotating power element, a reciprocating part located in coöperative position with relation to the lever and actuated by the power element, and means for connecting the reciprocating part and the lever.

36. Apparatus for distributing cotton, having, in combination, an endless traveling cotton conveyer, a receptacle, means for dis-
10 charging cotton from the conveyer into the receptacle, a lever operating such means, a reciprocating part, a feeler adapted to change its position with the quantity of cotton in the receptacle, and feeler-controlled means
15 for connecting the lever and the reciprocating part.

37. Apparatus for distributing cotton, having, in combination, a traveling belt, a receptacle, a gate for diverting cotton from
20 the belt into the receptacle, a gate-operating lever, a reciprocating part, a feeler adapted to change its position with the quantity of material in the receptacle, and feeler-con-
25 trolled means for connecting the lever and the reciprocating part.

38. Apparatus for distributing cotton, having, in combination, a traveling belt, a gate, a gate-operating lever, connections be-
tween the lever and the gate, and a part in

spring-controlled coöperation with the lever 3 to lock the gate in position and having a notch with one of its sides adapted to restrain the motion of the lever and oblique to the path of motion of the lever.

39. Apparatus for distributing cotton, 31 having, in combination, a traveling belt, a gate, a gate-operating lever, a power op-
erated reciprocating part located in coöp-
erative relation to the lever, and means for
connecting the reciprocating part and the 40 lever.

40. Apparatus for distributing cotton, having, in combination, a traveling belt, a gate, a gate-operating lever, a constantly 45 reciprocating power operated part, a trip-
lever mounted on the gate-operating lever in coöperative relation with the power operated part, a feeler, and feeler actuated means for tripping the trip-lever to thereby connect the reciprocating part with the gate-operating 50 lever.

In testimony whereof I affix my signature, in presence of two witnesses.
